Patented July 8, 1924.

UNITED STATES PATENT OFFICE.

GOTTFRIED SCHICK, OF TAMPA, KANSAS.

FANNING MILL.

Application filed October 29, 1921. Serial No. 511,317.

To all whom it may concern:

Be it known that I, GOTTFRIED SCHICK, a citizen of the United States, residing at Tampa, in the county of Marion and State 5 of Kansas, have invented certain new and useful Improvements in Fanning Mills, of which the following is a specification, reference being had to the accompanying drawings.

10 This invention relates to certain improvements in fanning mills and has relation more particularly to a device of this general character including a rotary screen into which is discharged grain to be separated and wherein novel and improved means is provided for vibrating the screen during its rotation and which vibration particularly serves to prevent clogging of the screen.

15 Another object of the invention is to provide a device of this general character including a rotary screen, together with means of a novel and improved character for driving the screen in a manner whereby frictional resistance is substantially eliminated 20 and the machine runs smoothly with a minimum of wear and tear.

An additional object of the invention is to provide a novel and improved device of 25 this general character which, by changing of the rotary screen, may be employed not only as a separator for the grain but for a grader and more especially in the grading of corn.

30 It is also an object of the invention to provide a device of this general character including a hopper adapted to discharge upon an associated screening element and wherein novel and improved means are provided to assure the desired flow of the grain 35 from the hopper to the screening element, together with additional means for regulating or controlling such flow.

The invention consists in the details of 40 construction and in the combination and arrangement of the several parts of my improved fanning mill whereby certain important advantages are attained and the device rendered simpler, less expensive and 45 otherwise more convenient and advantageous for use, as will be hereinafter more fully set forth.

The novel features of my invention will 50 hereinafter be definitely claimed.

55 In order that my invention may be the

better understood, I will now proceed to describe the same with reference to the accompanying drawings, wherein:

Figure 1 is an elevational view of a fanning mill constructed in accordance with an 60 embodiment of my invention;

Figure 2 is also an elevational view of my improved mill as herein disclosed but of the side opposite to that illustrated in Figure 1;

Figure 3 is a longitudinal vertical sectional view taken through my improved mill as herein disclosed;

Figure 4 is a fragmentary view partly in vertical section and partly in elevation of 70 the hopper as herein embodied;

Figure 5 is a fragmentary view in side elevation of the chute, the adjacent portion of the hopper being in section;

Figure 6 is a fragmentary view in perspective of the shield or guard arranged within the hopper;

Figure 7 is a view in elevation of the discharge end of the mill;

Figure 8 is a fragmentary view partly in 80 section and partly in elevation illustrating the driving connection for the separating element;

Figure 9 is a fragmentary sectional view taken longitudinally of the trough within 85 one of the bins, the associated conveyer being in elevation;

Figure 10 is a fragmentary sectional view taken longitudinally of the screening element and at the receiving end portion 90 thereof; and

Figure 11 is a fragmentary transverse sectional view taken through an element adapted for use in grading corn or the like.

As disclosed in the accompanying drawings, H denotes a housing of requisite dimensions and which has one end open and having its opposite end portion formed to provide a casing 1 for the fan F. The fan F includes a shaft 2 rotatably supported by the side walls 3 of the housing H and extending outwardly therefrom. One end portion of the shaft 2 is provided with a pinion 4 meshing with a relatively large gear 5 so that upon rotation of said gear 5, the fan F will be rotated at a relatively high speed. The gear 5 may be driven in any desired manner and as the driving means for this gear forms no part of the present invention, a description and 100 105 110

illustration thereof are believed to be unnecessary.

Disposed transversely of the housing H and bridging the space between the side walls 3 thereof is a beam or member 6. This beam or member 6 is positioned at the top portion of the housing H and has each of its end portions seating within a bracket 7 so that said beam or member 6 may be readily removed or applied as the occasions of practice may necessitate.

Supported by the housing H between the beam or member 6 and the adjacent end portion 8 of the housing H is a hopper A, said hopper being substantially V-shaped in section in a direction lengthwise of the housing H. The hopper A, when applied, is further supported by the suitably inclined plates or shoulders 9 carried by the side walls 3 of the housing H.

The central portion of the forward wall 10 of the applied hopper at the bottom thereof is provided with a discharge opening 11 opening into the downwardly and forwardly inclined chute C, said chute including the upstanding side walls 12. Coacting with the discharge opening 11 of the hopper A is a slide valve 14 providing means whereby the flow of the grain through said opening 11 may be regulated or controlled.

The valve 14 is provided with an upstanding extension 15 slidably engaged within a guideway 16. The outer or free end portion of said extension 15 carries a rack 17 disposed longitudinally thereof and with which meshes a pinion 18. The pinion 18 is fixed to a shaft 19 rotatably supported by the suitably spaced bearings 20 and said shaft is provided with an angularly disposed extension or arm 21 providing an operating member whereby the shaft 19 may be rocked in a direction to impart the desired movement to the valve 14.

Also coacting with the rack 17 is a resilient dog or pawl 22 whereby the valve 14 is held in its different adjusted positions. This dog or pawl, however, offers no resistance or obstruction to the desired movement of the valve 14 upon rocking or partial rotation of the shaft 19.

The side walls 12 of the chute C at a point in close proximity to the hopper A are provided with the transversely aligned open and arcuate slots 23 which are adapted to receive the opposite end portions of a shaft 24 extending outwardly of said side members 12 and adapted to be driven in a manner to be hereinafter more particularly referred to. Carried by the shaft 24 and substantially bridging the space between the side walls or members 12 are the blades 25 which, as the shaft 24 rotates, serve as a feeder to facilitate the flow of the grain along the chute C.

Connecting the upper marginal portions

of the side members or walls 12 of the chute C forwardly of the shaft 24 and the feeding blades 25 carried thereby is a cross member 26. Pivotedly engaged with said cross member 26 are the oppositely directed arms 27, the pivotal mountings 28 for said arms being inwardly of the inner ends thereof. The inner ends of said arms 27 are provided with the intermeshing teeth 29 whereby said arms are caused to rock in unison and in the same direction.

The outer end portions of the arms 27 extend outwardly of the side walls or members 12 and operatively engaged with said extended portions of the arms 27 and the extended portions of the shaft 24 are the links 30. Coacting with one extended portion of the shaft 24 is a spring element 31 which serves to constantly urge the shaft 24 inwardly of the slots 23.

In the event any foreign substance should pass through the discharge opening 11 of a size or character to interfere with the requisite rotation of the blades 25, the shaft 24 will move outwardly without interfering with the desired rotation thereof. The curvature of the slots 23 is such that as the shaft 24 is moved outwardly, the same will be lifted upwardly so that the blades 25 will be raised a distance sufficient to permit said foreign substance to pass therebelow. As soon as this substance or obstruction has passed the blades 25, the spring element 31 will operate to effect an automatic return of the shaft 24 to its normal position at the inner or closed ends of the slots 23.

Pivoted substantially midway its ends, as at 33, to the rear wall 34 of the applied hopper A is an elongated arm or rod 35, the lower end portion of which has affixed thereto a cross head 36. The cross head 36 is in relatively close proximity to the discharge opening 11 and has extending outwardly therefrom on an incline toward the forward wall 10 of the hopper A the tines 37, said tines being of a length to terminate at a point close to the forward wall 10 above the opening 11. The end tine 37 at their central portions are formed to provide downwardly disposed extensions or arms 38 while the central tines 37 are formed to provide the upwardly extending arms 39. These tines 37 and the depending arms 38 provide a shield or guard to minimize the passage of foreign substances or obstructions passing through the opening 11 and said tines 37, together with the arms 38 and 39, also provide means to agitate the grain immediately adjacent the opening 3 to facilitate the discharge of said grain through said opening.

The agitating function of the tines 37 is accomplished upon rocking movement of the arm or rod 35 and, as herein disclosed, the upper end portion of said arm or rod 35 is

provided with an angular extension 40 which is disposed through a slot 41 in the rear wall 34 of the hopper A.

Operatively engaged with the portion of this extension 40 exteriorly of the hopper A is an end portion of a rod 42, said rod extending transversely of the housing H and having its opposite end portion operatively engaged with the free end portion of an arm 10 a of a bell crank lever 43. The free end portion of the second arm b of this lever 43 has operatively engaged therewith an end portion of a rod 44.

The opposite end portion of the rod 44 is operatively engaged with a pulley 45 so that, as the pulley 45 is rotated, the resultant swinging movement of the bell crank lever 43 will reciprocate the rod 42 whereby the arm or rod 35 is rocked, resulting in the 20 desired functioning of the tines 37 and the arms 38 and 39 carried thereby.

In order that the grain within the hopper will offer no obstruction to the desired rocking movement of the arm or rod 35, I enclose the same within a hood or casing 46 fixed to the rear wall 34 of the hopper A, the lower face of said hood or casing 46 being open. The cross head 36 is immediately adjacent the open end of the hood or 30 casing 46 and the top plate 47 of said hood or casing is extended to overlie said cross head.

The pulley 45 is fixed to an end portion of a shaft 48 rotatably supported by and extending through a side wall 3 of the housing H. This shaft 48 extends inwardly of the housing H and to said inner portion is fixed a pinion 49 which, when the hopper A is applied, meshes with a pinion 50 fixed to 40 an extended end portion of the shaft 24 hereinbefore referred to so that, as the pulley 45 is rotated, said shaft 24 and the blades carried thereby will be properly driven.

45 S denotes an elongated cylindrical screening element having its opposite ends open and its peripheral wall foraminated, the openings 51 being arranged in a plurality of series, said series being spaced apart in a direction circumferentially of the element S with adjacent series in relatively close proximity one to the other. The openings of each series for a slight distance inwardly from the inner or receiving end of the elements 50 S are restricted or of materially less diameter than the remaining openings of the series. These smaller openings permit the discharge of weed seeds or other minute matter separated from the grain as delivered 60 within the element S from the hopper A.

Disposed axially of the element S is a shaft 52 and the element S is fixed to said shaft through the medium of the internal spiders 53. The shaft 52 has one end portion terminating inwardly of the receiving

end of the element S and its opposite end portion terminating beyond the outer or discharge end of the element S.

Depending from the central portion of the beam or member 6 is an arm 54, the lower portion of said arm being outwardly offset to extend within the receiving end of the element S so that said arm can serve as a bearing for the adjacent end portion of the shaft 52. The opposite or extended end 70 portion of the shaft 52 is received within a bearing 55 carried by a beam 56. One end portion of the beam 56 is pivotally engaged, as at 57, with the free or outer edge face of a side wall 3 of the housing H, while the opposite end portion of said arm is freely received within a bracket 58 carried by the outer edge face of the second side wall 3 of the housing H. The upper portion of the bracket 58 has associated therewith a removable member or pin 59 so that the free end portion of the beam 56 may be readily positioned within said bracket and held against displacement. The member or pin 59 is so positioned to 80 permit the beam 56 to have vertical swinging movement so that the screening element S may be vibrated and particularly in a manner to dislodge any grain or other matter which may seat within any of the openings 51 and which would otherwise clog said element.

The receiving end portion of the element S is provided with an internal annular member 60 to which the peripheral wall of the element S is secured. This annular member comprises a face gear with which meshes, when the element S is applied, a gear 61 fixed to the shaft 48 so that as said shaft 90 48 is driven, the element S is rotated.

100 It has been fully demonstrated in practice that by use of the face gear 60, the element S is driven with a minimum of frictional resistance and the machine in its entirety runs or operates smoothly with a minimum 105 of wear and tear.

110 The bottom of the housing H underlying the applied screening element S is of a construction to provide a pair of longitudinally spaced bins 62 and 63 each substantially V-shaped in cross section. The bin 62 underlies the portion of the element S provided with the restricted openings 51 so that the weed seeds or the like which are discharged through said restricted openings will be received therein. The lower portion of said bin 62 is open so that the seeds or the like received therein will be discharged within a removable drawer 64 or other container positioned therebelow. The bin 63 underlies the 115 larger openings 51 and the seed of the grain passes therethrough. The lower portion of this bin 63 is provided with a trough 65 discharging at one side of the housing H.

120 Disposed lengthwise of the trough 65 is 125

a shaft 66 supported adjacent each of its ends by a bearing 67. Carried by the shaft 66 and substantially bridging the space between the side walls 3 of the housing H is 5 a spiral conveyer 68 which, as the shaft 66 is rotated, serves to carry the grain received within the bin 63 to the delivery end of the trough 65. The delivery end of the trough 65 is provided with a spout 69 or 10 the like to facilitate the discharge of the grain within a sack, box or other container.

One end portion of the shaft 66 extends beyond one side of the housing H and to said extended portion is fixed a pulley 70. 15 Passing around the pulley 70 is an endless belt 71 which also passes over the pulley 45. The belt is also disposed around a pulley 72 fixed to an extended end portion of the fan shaft 2. By means of this belt 20 71, the pulleys 45 and 70 are driven from the shaft 2. The belt 71 at a point in close proximity to the pulley 72 is crossed so that the shaft 66 and the conveyer 68 will be rotated in the desired direction. Coacting 25 with one of the stretches of the belt 71, preferably the lower stretch, is a tightener 73.

The shaft 66 also has an end portion extending beyond the delivery opening of the trough 65 and fixed to said extended portion 30 is a worm 74 meshing with a worm gear 75. This worm gear 75 is fixed to the lower end portion of an upwardly and forwardly inclined shaft 76 rotatably supported by the adjacent side wall 3 of the housing H. The upper end portion of the shaft 76 has fixed thereto a cam member 77, the periphery of which is spiroidal in form to provide a 35 radially disposed shoulder 78 connecting the high and low points of the cam.

40 The free end portion of the beam 56 rests upon the periphery of the cam member 77 and as the shaft 76 rotates, the beam 56 will be gradually raised until it passes the high point of the cam member whereupon said beam 56 will drop abruptly. These movements of the beam 56 are transmitted to the 45 grinding element S whereby the same is effectively vibrated for the purpose hereinbefore referred to.

50 It is to be noted that the inner wall of the element S at its delivery end is free and unobstructed so that the tailings may readily pass therefrom.

55 It will also be understood that while the machine is in operation, the fan F will create a draft of air which will serve effectively to blow the chaff out through the open end of the housing H. To assure an effective draft or blast of air from the fan F, 60 the portion 79 of the housing H immediately below the fan F is disposed on a downward incline in a direction away from the bin 62 and toward the adjacent end of the housing H.

65 When it is desired to employ my improved

device for the grading of corn, the element B is employed and which is supported within the machine and driven in the same manner as has been hereinbefore set forth with respect to the element S. The peripheral 70 wall of the element B is provided with the longitudinally disposed corrugations 80 substantially V-shaped in cross section with adjacent corrugations in immediate proximity. The outer or apex portion of each of the 75 corrugations 80 is provided with a series of openings 81, the openings 81 above the bin 62 being smaller than the openings above the bin 63.

As the corn is discharged within the hopper from the chute C, the corrugations 80 provide grooves which cause the corn kernels to stand erect so that the passage of said kernels through the openings 81 is assured.

80 While clearly illustrated in the accompanying drawings, it is to be stated that the chute C is of a length to extend within the receiving end of the element S or the element B so that the desired discharge of grain therein is assured.

85 From the foregoing description it is thought to be obvious that a fanning mill constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

90 I claim:

1. In a fanning mill, bearing means carried by the casing, a bar pivoted at one end on the front of the casing and extending entirely thereacross, a shaft journaled in said bearing means and said bar and carrying a sieve, a shaft journaled exteriorly of the casing and having one end carrying a cam engaging said bar for oscillating the same, and means for simultaneously rotating both of said shafts.

115 2. In a fanning mill, a casing containing sifting means and equipped with means for producing a blast therethrough, a feed hopper leading into the sifting means, and a guard for obstructing the passage of foreign matter from the hopper, the guard comprising an arm carrying a cross member, fingers projecting from said cross member, certain of the fingers being formed with upstanding projections and others being formed with depending projections, said arm being pivoted intermediate its ends, an angle lever pivotally mounted and having 120 125 130

one end connected with said arm, a rotary element and a link eccentrically connected with the rotary element and connected with the other arm of the angle lever.

- 5 3. In a fanning mill, a casing containing sifting means and blast producing means, a hopper on the casing for feeding material into the sifting means, feed means operating within the hopper and a guard for

obstructing passage of foreign matter from 10 the hopper, said guard comprising a rotatably mounted member carrying fingers of angular formation, and an operative connection with a drive element for rocking said member. 15

In testimony whereof I hereunto affix my signature.

GOTTFRIED SCHICK.
